CIRCUIT CONTROLLING DEVICE

Harold L. Mekelburg, Milwaukee, Wis., assignor
to Cutler-Hammer, Inc., Milwaukee, Wis., a cor-
poration of Delaware

Application February 18, 1937, Serial No. 126,367

10 Claims. (Cl. 200—6)

This invention relates to circuit controlling devices, and while not limited thereto is particularly applicable to multi-pole reversing switches for electric motors.

5 The invention has among its objects to provide an exceedingly compact and rugged control switch consisting of parts which can be economically manufactured and readily assembled.

Another object is to provide a control switch 10 having cooperating stationary and movable contact elements of novel form.

Another object is to provide a control switch of the aforesaid character in which the stationary and movable contact elements are made 15 up almost entirely of molded insulating parts and sheet metal stampings.

Another object is to provide a reversing switch for electric motors having a plurality of poles each consisting of three stationary contacts and 20 a cooperating rotatable contact element having a plurality of pairs of removable bridging contacts associated therewith.

Various other objects and advantages of the invention will hereinafter appear.

25 The accompanying drawings illustrate an embodiment of the invention which will now be described, it being understood that the embodiment illustrated is susceptible of modification without departing from the spirit and scope of the appended claims.

In the drawings,

Figure 1 is a side elevational view of a control switch embodying the invention, parts of the switch being shown in section;

30 Fig. 2 is a front elevational view of the control switch shown in Fig. 1, a cover associated with the enclosing casing for the switch being removed;

Figs. 3 and 4 are sectional views on lines 3—3 35 of Fig. 1 illustrating the switch in off position and in one of its on positions;

Figs. 5, 6 and 7 are perspective views of certain of the parts shown in Figs. 1 and 2;

Fig. 8 is a sectional view on line 8—8 of Fig. 40 2, and

Fig. 9 is a diagrammatic view illustrating a typical circuit arrangement for the control switch shown in Figs. 1 and 2.

The control switch illustrated in the drawings 50 includes a rotatable contact element 1 having a plurality of pairs of insulated bridging contacts 2, 3 and 4 associated therewith which cooperate with sets of stationary contacts 5, 6 and 7, respectively, carried by an insulating base 8. Said 55 parts are mounted within an enclosing casing

comprising a frame 9 having a rear wall 10 and top and bottom walls 11 and 12, and an associated U-shaped cover 13.

More specifically, contact element 1 is provided with a plurality of molded insulating sections 14 which are mounted side by side upon an operating shaft 15. Said insulating sections are of like construction and as best shown in Figs. 6 and 7 each of the same is provided with a segmental body portion 16 having a centrally disposed hub projection 17 on the base thereof which is provided with an opening for receiving shaft 15. The curved face of body portion 16 is provided with a centrally disposed peripheral groove 18 and the side faces of said body portion are each similarly formed to provide grooved end projections 19—19, key portions 20—20 extending inwardly from said end projections and a groove 21 extending between said end projections. Also the body portion 16 is formed to provide a centrally disposed tongue projection 22 on one face thereof and a centrally disposed groove 23 on the opposite face thereof.

In the embodiment illustrated there are four 25 insulating sections 14 mounted upon shaft 15, and as shown in Fig. 1 said insulating sections are clamped between a nut 25 which is threaded on said shaft adjacent the lower end thereof and a star wheel 26 which is secured to said shaft 30 adjacent the upper end thereof by a pin 27. The insulating sections 14 are arranged so that the tongue projection 22 and groove 23 of adjacent sections engage to prevent relative rotation of said sections, and as shown in Figs. 1 and 8 35 the tongue 22 of the top insulating section engages within a recess 28 in star wheel 26 to lock the said insulating sections against rotation with respect to shaft 15. The hubs 17 of insulating sections 14 are of such length that a narrow 40 space is provided between the opposing faces of adjacent end projections 19. Also the insulating sections 14 are assembled upon shaft 15 with coil springs 30 between the opposing faces of said sections, said springs being held in position 45 by the opposing faces of the grooves 21.

The three pairs of bridging contacts are removably mounted between the opposing faces of the four insulating sections 14, and as shown in Fig. 7 each of said bridging contacts comprises 50 an elongated sheet metal stamping 31 having curved contact portions 32—32 on opposite ends thereof and an intermediate shank 33 which is of reduced width to provide opposing shoulders 34—34 on opposite sides of the contact. Also 55

the shank 33 is provided with a centrally arranged enlarged portion 35 having a struck out projection 36 on one face thereof. As is apparent from Fig. 7 the shank 33 on each of the 5 bridging contacts is insertable edgewise between the end projections 18—19 of its associated insulating sections 14 into a position wherein the same clears said end projections. The contact can then be rotated about its longitudinal axis 10 into a position wherein the shoulders 34 on opposite sides thereof interlock with the side faces of the key portions 20 on the opposing faces of the associated insulating sections 14. As is apparent, the contact is then locked against both 15 lateral and longitudinal movement with respect to its associated insulating sections 14. Also the contact is biased to move outwardly under the action of its associated spring 30, such movement being limited by engagement of its shank 33 with 20 the shoulders formed by end projections 19 on the associated insulating sections. The bridging contacts are thus normally held in engagement with their associated end projections 19 and said projections are so designed that each 25 pair of contacts is normally held in substantially parallel relation as illustrated in Fig. 3. As is apparent, the bridging contacts when mounted as hereinbefore described are adapted to rock upon the ends of their associated springs 30 and 30 are also held in assembled position upon insulating sections 14 by said springs.

Shaft 15 is journaled within openings in the top and bottom walls 11 and 12 of bracket 9 and the upper end thereof has an operating lever 31 fixed thereto. As hereinbefore stated, shaft 15 has a star wheel 26 secured thereto by a pin 27 and as shown in Figs. 6 and 8 the periphery of said star wheel is provided with notches 38, 39 and 40 to be engaged by a roller 41. Roller 41 is rotatably mounted upon a lever 42 which is pivoted as shown at 43 upon a bracket 44 fixed to the top wall 11 of frame 9. Lever 42 is biased to maintain roller 41 in engagement with the periphery of star wheel 26 by a spring 45 which is connected between the free end of said lever and a projection 46 on bracket 44. As is apparent, roller 41 cooperates with notch 39 to yieldingly hold contact element 1 in an intermediate position shown in Fig. 3, and said roller also cooperates with notches 38 and 40 to yieldingly hold said contact element in opposite extreme positions, one of which is illustrated in Fig. 4.

As hereinbefore stated the pairs of bridging contacts 2, 3 and 4 cooperate with sets of stationary contacts 5, 6 and 7, respectively, carried by an insulating base 8. Insulating base 8 is formed of molded insulating material and is arranged in front of contact element 1. Said insulating base is rectangular in form and the upper side of said base is provided with a pair of supporting lugs 48—48 which are secured to bracket 44 by screws 49 while the lower side thereof is provided with a supporting lug 50 which is secured by a screw 51 to a bracket 52 fixed to the lower wall 12 of frame 9.

The three sets of stationary contacts 2, 3 and 4 are horizontally aligned with respect to their cooperating pairs of stationary contacts 5, 6 and 7 and each of said sets of stationary contacts includes three contacts designated by reference characters a, b and c. Contacts b are arranged intermediate the contacts a and c and as shown in Fig. 2 corresponding contacts of sets 2, 3 and 4 are vertically aligned.

75 The stationary contacts are of like construction,

and as shown in Fig. 5 each of the same comprises an elongated sheet metal stamping formed to provide a terminal portion 54 and a hook contact portion 55 on one end of said terminal portion. Insulating base 8 is provided with individual 5 openings 56 for receiving the several stationary contacts and as shown in Figs. 1 and 3 the rear face of said insulating base is formed to provide V-shaped projections 57 for engaging the hook contact portions 55 of the several stationary contacts. The terminal portion 54 of each contact is bent over in the direction of its hook contact portion 55 to engage the front face of insulating base 8 and as shown in Fig. 5 said terminal portion is provided with an opening 58 to facilitate bending thereof. As is apparent from the foregoing, the stationary contacts are securely held within the openings 56 in insulating base 8. The terminal portion 54 of each stationary contact is provided with a tapped opening 59 for receiving a 20 binding screw and is also provided with a wire receiving opening 60 for receiving connections which may be arranged as shown in Fig. 2.

As shown in Figs. 1 and 2 the front face of insulating base 8 is provided with horizontally arranged ribs 61 which form horizontal wiring passages in the spaces between the sets of stationary contacts 5—6 and 6—7. Also as shown in Figs. 1 and 2 the rear face of insulating base 8 is provided with rearwardly projecting side ribs 30 62—62 and a plurality of horizontally arranged ribs 63 extending between said side ribs, the latter ribs being aligned with the grooves 18 in the insulating sections 14 and acting as barriers between the sets of contacts. As is apparent, the 35 contact element 1 is movable in opposite directions out of the intermediate position shown in Fig. 3 to bridge stationary contacts b with stationary contacts a and c selectively.

Referring now to Fig. 9 the above described 40 control device is shown as connected to establish reverse power connections for a three phase alternating current motor M. A supply circuit for said motor is indicated by lines L¹, L² and L³, and as is apparent upon movement of contact element 45 1 into a position to engage stationary contacts a and b the supply lines L¹, L² and L³ are respectively connected to terminals T², T¹ and T³ of the motor. However, upon movement of contact element 1 into a position to bridge stationary contacts b and c the supply lines L¹, L² and L³ are respectively connected to terminals T³, T¹ and T² of the motor. It is, of course, apparent that the above described control device may be connected to establish reverse power connections for motors 55 of other types.

What I claim as new and desire to secure by Letters Patent is:

1. In an electric switch, in combination, co-operating stationary and movable contacts, a support for said movable contacts comprising molded insulation having formed therein cavities to support said movable contacts and to permit rocking movement thereof individually, and springs mounted within said support for normally holding said movable contacts in given positions and to oppose rocking movements thereof, said movable contacts being removable from said support by manipulation and said support being provided with shoulders for engaging said contacts to secure the same against dislocation by forces met with in normal operations.

2. In an electric switch, in combination, co-operating stationary and movable contacts, supporting means for said movable contacts com- 75

prising molded insulating sections arranged side by side and having formed therein complementary cavities to receive and seat portions of said movable contacts for rocking movement of the latter individually, and springs mounted between said insulating sections to yieldingly hold said movable contacts in engagement with their cooperating seats and to oppose their rocking movements, said contacts being removable from said support by manipulation, and said insulating sections being formed with shoulders which cooperate with said movable contacts to prevent dislocation thereof by forces met with in normal operations.

15 3. In combination, stationary contacts, cooperating movable contacts each comprising a shank having contact portions at opposite ends thereof, a molded insulating support for said movable contacts formed to provide cavities to receive and seat the shank portions of said movable contacts for rocking movement of the latter contacts individually, and springs mounted within said support to yieldingly hold said movable contacts in their seats and to oppose their rocking movements, said movable contacts by manipulation being readily removable from said support and said support being formed with shoulders securing said cooperating contacts against dislocation by forces met with in normal operations.

20 4. In combination, stationary contacts, cooperating movable contacts each comprising a shank and contact portions at opposite extremities of said shank, a drum support for said movable contacts comprising a plurality of insulating sections mounted side by side and having cooperating faces formed to provide cavities to receive and seat the shanks of said movable contacts for rocking movement of the latter individually, and springs mounted between said sections to yieldingly hold said cooperating contacts in their seats and to oppose their rocking movements, said sections providing slots enabling said contact shanks by manipulation to be inserted in their seats and to be removed at will, and said sections being 25 molded with shoulders securing said cooperating contacts against dislocation by forces met with in normal operation.

25 5. In combination, cooperating stationary and movable contacts, a molded insulating support for said movable contacts having formed therein cavities to receive and seat a pair of said movable contacts in an opposed relation for rocking movement of the latter individually, and a coil spring mounted in said support and interposed between 30 said opposed contacts to yieldingly hold both in their seats and to oppose their rocking movements, said cooperating contacts being removable from said support by manipulation, and said support being formed with shoulders securing 35 said cooperating contacts against dislocation by forces met with in normal operation.

30 6. In a movable switch element, in combination, a shaft, drum sections of molded insulation mounted on said shaft, said drum sections being 35 alike and interlocking and each being molded with cavities in opposite sides, a plurality of contacts each having a portion insertable between adjacent drum sections for seating within the cavity provided jointly by such adjacent drum sections, and springs mounted in cavities in said 40 drum sections to bear against and to hold said contacts seated, said contacts having rocking movement in said cavities against the bias of said springs and said drum sections being molded

45 with shoulders to secure said contacts against dislocation by normal forces while permitting their ready removal by manipulation.

7. In an electric switch, the combination with an insulating base having an opening therein, of 5 a combined contact and terminal member comprising a reflexed metal strip mounted within said opening and having a hook contact portion and a terminal portion engaging opposite faces of said base, one of the faces of said insulating 10 base being formed to fit within said hook contact portion.

8. In a reversing switch for electric motors, in combination, a rotatable insulating support having a plurality of pairs of bridging contacts yieldingly mounted thereon, each of said pairs of bridging contacts being arranged in opposed relation on opposite sides of the axis of said support, and said support being rotatable in opposite directions out of an intermediate off position into 15 extreme on positions, a fixed insulating base and a plurality of stationary contact sets mounted upon said base each associated with one of said pairs of bridging contacts, each of said stationary contact sets including a contact to be selectively 20 engaged by its associated bridging contacts in the extreme on positions of said support and two contacts arranged on opposite sides of said former contact each to be engaged by one of its associated bridging contacts in one of the extreme on 25 positions of said support.

9. In a reversing switch for electric motors, in combination, a rotatable insulating support having a plurality of pairs of bridging contacts yieldingly mounted thereon, each of said pairs of 30 bridging contacts being arranged in opposed relation on opposite sides of the axis of said support, and said support being rotatable in opposite directions out of an intermediate off position into extreme on positions, a fixed insulating base of 35 molded insulating material having ribs extending transversely of the paths of said bridging contacts, and a plurality of stationary contacts carried by said base to cooperate with said bridging contacts in the extreme on positions of said support, each of said stationary contacts comprising a reflexed metal stamping having a hook contact 40 portion fitting over one of the ribs on said base and a terminal portion extending through said base for securement and wiring.

10. In a reversing switch for electric motors, in combination, a rotatable insulating support having a plurality of pairs of bridging contacts yieldingly mounted thereon, each of said pairs of bridging contacts being arranged in opposed relation on opposite sides of the axis of said support and said support being rotatable in opposite directions out of an intermediate off position into extreme on positions, a fixed insulating base of 45 molded insulating material having one of its faces 50 formed to provide a plurality of ribs extending at right angles to the axis of said insulating support and located between each of said pairs of bridging contacts and a plurality of projections extending between said ribs and a plurality of 55 stationary contacts carried by said base to cooperate with said bridging contacts in the extreme on positions of said support, each of said stationary contacts comprising a reflexed metal stamping having a hook contact portion fitting over 60 one of the projections on said base and a terminal portion extending through said base for securement and wiring.
